UNITED STATES PATENT OFFICE.

MONTAGU SAUNDERS, OF LONDON, ENGLAND.

VARIABLE-SPEED GEARING.

No. 880,578.

Specification of Letters Patent.

Patented March 3, 1908.

Application filed April 6, 1906. Serial No. 310,271.

To all whom it may concern:

Be it known that I, MONTAGU SAUNDERS, gentleman, a subject of the King of England, residing at 67 Springfield road, St. John's 5 Wood, London, N. W., England, have invented certain new and useful Improvements in Variable-Speed Gearing Applicable to Cycles, Motor-Cars, and the Like, of which the following is a specification.

This invention relates to multiple or variable gearing applicable to bicycles, tricycles, motor cars, and the like.

The description hereinafter contained refers more particularly to that form of my 15 invention which I propose to apply to bicycles, but I wish it to be understood that I do not thereby intend to restrict my said invention to that application only.

In the accompanying drawings I have 20 shown two forms of my said invention, Figures I to VI referring to the one form, and Fig. VII to the other.

The same numbers refer to the same parts in Figs. I to VI, and to the same or similar 25 parts in Fig. VII.

Fig. I is a longitudinal half-section. Fig. II is a transverse section of the line II—II, looking in the direction of the arrow *a*. Fig. III is a similar section on the line 30 III—III looking in the direction of the arrow *b*. Fig. IV is a similar section on the line IV—IV looking in the direction of the arrow *c*. Fig. V is a similar section on the line V—V, looking in the direction of the 35 arrow *d*. Fig. VI is a similar section on line VI—VI looking in the direction of the arrow *e*. Fig. VII shows a modification.

In Fig. I the back-wheel sprocket 1, (which may, if desired, be a free wheel 40 sprocket of any convenient construction, and is shown in diagrammatic form only), is mounted upon and adapted to drive the sleeve 2, which carries the internally-toothed flanged ring 3. This ring 3 meshes 45 with a pinion or pinions 4, which are also in mesh with the toothed sleeve 5, surrounding the main axle 6, and are mounted on studs or pivots 7, around which they revolve freely, the whole system forming what is 50 known as an epicycle train.

The studs or pivots 7 are either integral with or are fixed by any convenient means to, the annular ring 8, and they may conveniently be formed with heads, attached 55 to a cylinder 9 by suitable means (such as a screw thread, screwing up to a shoulder),

and at the other end of the said cylinder there is similarly attached another annular ring 8^a, which also carries a pinion or pinions 4^a, suitably mounted on studs or pivots 7^a, 60 so as to allow of their revolving freely thereon. The pinions 4^a mesh with the internally-toothed ring 3^a, and also with the toothed sleeve 5^a, forming therewith a second epicyclic train, the proportions whereof may differ from those of the first mentioned train. 65

The sleeve 5^a is connected to the hub-shell 10 by a one-way clutch 11 of any convenient description (contained in the hub-side 10^a), adapted to allow the hub-shell to 70 over-run the said sleeve in the forward direction, but to prevent the sleeve, when rotated forward, from over-running the hub-shell. The internally-toothed ring 3^a may either be rigidly attached to the hub-shell 75 by any convenient means (as shown in Fig. I), or may be connected by any suitable form of one-way clutch, permitting the hub-shell to over-run the said ring in the forward direction only. 80

Rigidly attached to the sleeve 5 by any convenient means, is an inner cylinder 12, which is formed with one or more slots in the direction of its longitudinal axis, and within this inner cylinder there is placed 85 another cylinder 13, which while capable of sliding freely into or out of the cylinder 12, cannot revolve around its longitudinal axis independently of the cylinder 12 by reason of feathers 13^a working in said slots. The 90 sliding cylinder 13 carries at that end thereof which is furthest away from the sleeve 5, a set of ratchet teeth 14, or the like, adapted to engage with a corresponding set of teeth 14^a formed on the annular ring 8^a, and so 95 shaped as to prevent backward movement of the cylinder 13 (and therefore of the cylinder 12 and the sleeve 5) independently of the annular ring 8^a, cylinder 9, and ring 8, so long as the said teeth are in engagement. 100 A spiral spring 15, which may conveniently be inserted between the backs of the teeth 14, and a flange 16 formed on the cylinder 12, tends to keep the teeth 14 normally in engagement with the corresponding set 14^a 105 on the annular ring 8^a, but allows them to be drawn out of engagement by the sliding cylinder 13 telescoping into the cylinder 12.

The sliding cylinder 13 also bears, at that end thereof which is nearest to the sleeve 5, 110 another set of ratchet teeth 17, or the like, adapted to engage with a corresponding set

of teeth 18, formed on the sliding stop 19, and so shaped as to prevent backward movement of the cylinder 13 (and therefore of the cylinder 12 and sleeve 5) relatively to the 5 stop 19, so long as the two sets of teeth are in engagement.

The sliding stop 19 is preferably in the form of a short sleeve or cylinder, surrounding the axle 6, along which it is capable of 10 sliding to and fro, within certain limits, but around which it is incapable of rotating, by reason of one or more feathers 20 formed thereon which fit into corresponding grooves in the stop. The said stop carries, in addition 15 to the teeth 18, a further set of ratchet teeth 21, adapted to engage with a corresponding set of ratchet teeth 21^a on the sleeve 5^a and so formed as to prevent forward motion of the said sleeve relatively to the stop, 20 so long as the two sets of teeth are in engagement.

The teeth 18 and 21 on the stop 19 may be brought into and out of engagement with the teeth with which they respectively correspond, by sliding the stop along the axle 25 by any suitable means, and the following method may conveniently be employed. The axle 6 is made hollow from end to end, and in the bore so formed is inserted a rod 30 22, or the like, which is capable of being moved towards either end of the axle. To the end of the rod nearest to the sprocket is attached the actuating cable or chain 23, or the like, which passes out of the axle and 35 enables the rider, by suitable well known means, to draw the rod towards the sprocket. The other end of the rod 22 projects into the step 24, and carries on its end a button 25, fixed thereto by any convenient method, 40 and between the said button and the end of the axle is placed a spiral spring 26, which being normally under slight compression, tends to keep the rod 22 away from the sprocket end of the axle, but allows it nevertheless to be drawn towards the sprocket by 45 the cable. Alternatively, the spring may be contained within the axle in the well known way. The axle 6 is slotted for a small portion of its length between the feathers 20 and a pin 27 passing through the 50 said slots, connects the rod 22 to the stop 19, so that any movement of the said rod either towards or away from the sprocket is communicated to the stop.

55 The axle 6 is rendered incapable of rotation by any convenient means, say by cutting flats upon its ends where they pass through the chain - stays. The only movement of which the stop 19 will be capable will therefore be for a relatively short distance backwards or forwards along the axle.

The action of the mechanism is as follows, starting with the parts in the relative positions shown in Fig. I where the tension on 60 the actuating cable 23 is relaxed, and the

spring 26 has drawn the rod 22 to its position furthest away from the sprocket. The teeth 21 on the stop 19 are now in engagement with the teeth 21^a on the sleeve 5^a, which is therefore incapable of rotating forward, and the teeth 14 on the sliding cylinder 13 are also in engagement with the teeth 14^a on the annular ring 8^a; on the other hand, the teeth 17 are out of engagement with the teeth 18. Upon forward motion being imparted by the sprocket 1 to the sleeve 2, the epicyclic train nearest to the sprocket will be driven "solid" that is to say, without any relative movement between its parts, and the cylinder 9 will be rotated turn for turn 70 with the sprocket. As, however, the sun-wheel on the sleeve 5^a is incapable of rotating forward, the epicyclic train of which it forms part will come into action, and the ring 3^a and consequently the hub-shell 10, will be 80 driven forward at an increased rate of speed, as compared with the sprocket. If now the stop 19 be drawn by the changing cable towards the sprocket sufficiently far to take the teeth 21 out of engagement with the teeth 21^a, but not far enough to bring the teeth 17 and 18 into engagement, the epicyclic train nearest to the sprocket will, when driven forward, still continue to rotate "solid" as before, and the cylinder 9 will 90 still be rotated turn for turn with the sprocket, but as the sun-wheel on the sleeve 5^a is no longer held stationary, the epicyclic train of which it forms part will also be driven "solid" and the hub-shell will therefore 95 be driven forward thereby turn for turn with the sprocket. Lastly, if the stop be drawn still nearer towards the sprocket, so that first the teeth 18 are brought into engagement with the teeth 17 on the cylinder 105 13, and secondly, the teeth 14 on the sliding cylinder 13 are drawn out of engagement with the teeth 14^a on the annular ring 8^a, the sun-wheel on the sleeve 5 will, by reason 110 of the engagement of the teeth 17 and 18, be unable to rotate backwards, and thus the cylinder 9 will, on the forward drive, be rotated forward at a slower rate of speed than the sprocket. But as the epicyclic train nearest to the stop now revolves "solid" 115 (as on the middle or normal speed), the hub shell will be driven forward at the same rate of speed only as the cylinder 9, that is to say, at a lower rate than the sprocket.

All the working parts are preferably 120 mounted on ball bearings, as shown in Fig. I, 28 and 28^a being balls of the main bearings, and 29 and 29^a, the adjusting cones thereof; one of the balls of the bearing which comes into action, on the high or low speed being 125 employed, is shown at 29^b. I find it convenient to make the screw-thread on the sprocket end of the axle left-handed, and that on the other end right-handed, so as to prevent the adjusting cones from tightening 130

up under rotation. The cylinder 9 may be retained in its position laterally by the bearing 30, or other suitable means, and the sleeves 5 and 5^a may conveniently be carried in bearings formed in the rings 8 and 8^a respectively, as shown in Fig. I, the said bearings serving also to keep the said sleeves in their places laterally, but of course other suitable means may be employed. If the last mentioned bearings be used, the balls therein may conveniently be introduced through a hole bored radially in the said rings, a movable plug being subsequently inserted, the inner end of which forms part of the ball race; the said plug may be secured by any convenient means, say by a set screw partially passing into the said plug, so that the part of the ball race thereon may be properly alined.

I prefer to make the teeth 14 on the cylinder 13, and the corresponding set 14^a on the annular ring 8^a, ratchet shaped as described, so as to permit of the low speed being put into action while the machine is being wheeled backwards, without any risk of damaging the mechanism. I also prefer to make the teeth 21 on the stop 19, and the corresponding set 21^a on the sleeve 5^a, ratchet shaped as described, although, especially if either a free wheel sprocket be employed, or the tooth ring 3^a be connected to the hub-shell by a oneway clutch, this is not essential. It is essential, however, that the teeth 17 on the sliding cylinder 13 and the teeth 18 on the stop 19, should be ratchet shaped as described so as to permit of their being brought into contact during the forward drive while the teeth 14 on the cylinder 13 are still in engagement with the corresponding set 14^a on the annular ring 8^a, and of those latter being disengaged, during the forward drive, by the cylinder 13 being drawn into the cylinder 12.

In the form of my invention above described, I have shown the epicyclic trains caused to drive "solid" by the temporary locking together of two of their members respectively, but it is not essential to my invention that the "solid" drive should be effected by the locking of the two particular members as described, the locking of any two which will effect the desired object being within the spirit of my invention. The same remark applies to the modification illustrated in Fig. VII.

I have not, in describing my invention, described any means of moving the actuating cable, or retaining it in its position, when moved from time to time, as such means are well known and commonly used. A slightly modified form of this mechanism is illustrated in Fig. VII. The principle and operation of this form of the mechanism will abundantly appear by the description hereinabove given. It may be noticed that this form, Fig. VII scarcely differs from the other, but will be

more easily manufactured. Comparing the same with Fig. I it will be seen that the parts marked 8 and 9 Fig. I are in Fig. VII represented as a single piece A⁸. I am enabled wholly to dispense with the internal bearing shown at 30 in Fig. I, by substituting therefor the bearing 30^a. At B a one way clutch is shown between the sprocket wheel 1 and the remainder of the mechanism; this is of known construction and calls for no further description.

Claims.

1. In a variable speed gear the combination of a fixed axle and a hub shell rotating thereon, with a sprocket wheel, a first epicyclic train whereof one member rotates with said sprocket wheel, a second epicyclic train one member whereof rotates with the driven hub, an intermediate carrier carrying one member of each train, and means capable of being so operated as either to prevent relative movement of the members of both trains on the forward drive or to lock either sun-wheel to the fixed axle on the forward drive and simultaneously cause the train of which such locked sun-wheel forms part to become operative, while the parts of the other train remains locked against relative movement.

2. In a variable speed gear the combination of a fixed axle and a hub shell rotating thereon, with a sprocket wheel, a first epicyclic train whereof the outermost member is driven by said sprocket wheel, a second epicyclic train whereof the outer member is rigidly attached to the driven hub, a pinion carrier between the two trains, studs on either side thereof carrying the planet pinions of said trains, and means capable of being so operated as either to prevent relative movement of the parts of both trains on the forward drive or to lock either sun-wheel to the fixed axle on said forward drive and simultaneously cause the train of which said locked sun-wheel forms part to become operative, while the parts of the other train remains locked against relative movement.

3. A variable speed gear consisting of a non-rotating spindle, a hub shell mounted thereon, an internally toothed wheel driven by the driving element and a driven internally toothed wheel attached to the hub-shell, sunwheels, an intermediate carrier, planet pinions mounted thereon and gearing with said internally-toothed wheels and sunwheels, a one way clutch between one sunwheel and said carrier, a one-way clutch between the other sun-wheel and the driven member, and a stop capable of locking either sun-wheel to the spindle, the whole so arranged that the pinions are incapable of being disengaged from the internally-toothed wheels and sun-wheels.

4. A variable speed gear consisting of a non-rotating spindle, a hub shell mounted thereon, an internally-toothed wheel driven

by the driving element, and a driven-internally toothed wheel attached to the hub shell, sun wheels, an intermediate carrier, planet pinions mounted thereon and gearing 5 with said internally-toothed wheels and sun-wheels, a sliding one way clutch between one sun-wheel and said carrier, a one way clutch between the other sun-wheel and the driven member, and a sliding stop capable of locking 10 either sun-wheel to the spindle, the whole so arranged that the pinions are incapable of being disengaged from the internally-toothed wheels and sun-wheels.

5. A variable speed gear consisting of a 15 non-rotating spindle, a hub shell mounted thereon, an internally-toothed wheel driven by the driving element, and a driven internally toothed wheel attached to the hub shell, sun wheels, an intermediate carrier, 20 planet pinions mounted thereon and gearing with said internally-toothed wheels and sun-wheels, a sliding spring controlled one way clutch between one sun-wheel and said carrier, a one way clutch between the other sun- 25 wheel and the driven member, and a controlled stop capable of locking either sun-wheel to the spindle, the whole so arranged that the pinions are incapable of being disengaged from the internally-toothed wheels and 30 sun-wheels.

6. In a variable speed gear the combination with a driven hubshell of internally-toothed driving and driven members, an intermediate pinion-carrier, two sets of planet 35 pinions and sun-wheels, a locking device between one sun-wheel and said carrier, a one-way clutch between the other sun-wheel and the driven member, a hollow fixed axle, a non-rotating stop sliding thereon, a control- 40 rod sliding in said hollow axle, a cross-pin connecting said rod to said stop, and rod-controlling devices.

7. In a variable speed gear the combination with a driven hub-shell of internally-toothed driving and driven members, an intermediate pinion-carrier, two sets of planet 45 pinions and sunwheels, a locking device between one sun-wheel and said carrier, a one way clutch between the other sun-wheel and 50 the driven member, a hollow fixed axle, a non-rotating stop sliding thereon, a control-rod sliding in said hollow axle, a cross pin connecting said rod to said stop, a spring

controlling said rod in one direction and a pulling device controlling said rod in the 55 other direction.

8. In a variable speed gear the combination with a driven hub-shell of internally-toothed driving and driven members, an intermediate pinion-carrier, two sets of planet- 60 pinions and sun-wheels, a sliding locking device between one sun-wheel and said carrier, a spring operating same, a one-way clutch between the other sun-wheel and the driven member, a hollow fixed axle, a non-rotating 65 stop sliding thereon, a control-rod sliding in said hollow axle, a cross-pin connecting said rod to said stop, a spring controlling said rod in one direction and a cable controlling same in the other direction. 70

9. In a variable speed gear the combination with a driven hub-shell and a hollow non-rotating axle, of a sprocket wheel, an internally-toothed wheel carrying same, a sun-wheel planet pinions gearing with said sun-wheel and said internally-toothed wheel; a slotted extension of said sun-wheel, a clutch element sliding therein having two sets of ratchet teeth, a spring controlling said element, a pinion carrier carrying two sets of 80 pinion-studs on the outer faces thereof and having a set of ratchet teeth on one inner face, a second sun-wheel having ratchet teeth on the inner face thereof and one element of a one-way clutch on an outer extension thereof, 85 a second internally-toothed wheel rigidly attached to the driven hub and having the other element of said one-way clutch thereon, a second set of planet pinions mounted on studs on said carrier and gearing with said 90 second sun and internally-toothed wheels, a sliding non-rotatable stop having two sets of ratchet teeth capable of engaging with corresponding teeth on clutch element sliding on extension of first sun-wheel and on second 95 sun-wheel respectively; a spring-controlled shifting rod in hollow axle rigidly connected to said sliding stop, and operating means attached to said rod.

In testimony whereof I have hereunto set 100 my hand in the presence of two witnesses.

MONTAGU SAUNDERS.
